UNITED STATES PATENT OFFICE.

MICHAEL J. MCKINNON, OF PORTLAND, OREGON.

DUMPING-CAR.

SPECIFICATION forming part of Letters Patent No. 622,382, dated April 4, 1899.

Application filed December 28, 1898. Serial No. 700,531. (No model.)

To all whom it may concern:

Be it known that I, MICHAEL J. MCKINNON, a citizen of the United States, residing at Portland, in the county of Multnomah and State of Oregon, have invented new and useful Improvements in Dumping-Cars, of which the following is a specification.

My invention relates to that class of dumping-cars which embrace bodies susceptible of being canted longitudinally in one direction and laterally in opposite directions; and it consists in the peculiar and advantageous construction, certain novel combinations, and the adaptation of parts hereinafter described, and particularly pointed out in the claims appended.

In the accompanying drawings, Figure 1 is a transverse section of my improved car, taken in the plane indicated by broken line 1 1 of Fig. 2. Fig. 2 is a longitudinal central section taken in the plane indicated by broken line 2 2 of Fig. 1. Fig. 3 is an enlarged detailed transverse section taken in the plane indicated by broken line 3 3 of Fig. 2.

In the said drawings similar letters designate corresponding parts in all of the views, referring to which—

Are axles carrying wheels B and journaled at their ends in boxes C, and D are longitudinal stringers connected to and supported by the boxes. On these stringers are mounted and suitably secured a transversely-disposed pedestal E and a similarly-disposed pillow-block F, the former being arranged between the axles and the latter adjacent to one end of the car, as best shown in Fig. 2.

The pedestal E has its upper edge inclined in opposite directions, as indicated by a, and in the preferred embodiment of the invention it is provided in its rear side with a curvilinear recess b and is also provided with a longitudinal central aperture c, which intersects the recess after the manner shown in Fig. 2.

G is a ball mounted and secured upon the upper end of the pedestal, and H is the car-body, which is provided at the center of its under side with a socket I, receiving the ball G, and is therefore adapted to be swung up and down longitudinally and also laterally.

In order to guide the body H in its lateral movements and hold it against swinging in

a horizontal direction incident to its longitudinal inclination, the circular bar J is provided. This bar J is arranged to move 55 through suitable guides d, located in the recess b of the pedestal, and is connected at its ends in a hinged manner to the under side of the body H by pintles e, which are disposed transversely with respect to the body 60 for a purpose presently described. These pintles e are also arranged in the same transverse and horizontal planes as the ball-and-socket bearing between the pedestal and body; and hence it will be seen that they will in no 65 manner interfere with the longitudinal or endwise inclination of the body. While this is so, the bar J, being held against horizontal movement by its guides, will effectually prevent the body from swinging or swaying horizontally incident to its longitudinal or endwise inclination. When canted longitudinally, the forward portion of the body is designed to rest on the forward ends of the stringers D, which are preferably beveled, as 75 indicated by f, and when said body is in its normal position its rear end is supported by the pillow-block F and is detachably secured to said block through the medium of a pivoted link g and a keeper h, which latter is 80 designed to be turned when it is desired to release the rear end of the body to permit of the same being canted longitudinally.

In order to permit of the body H being inclined laterally in either direction without the necessity of disconnecting the end of the same from the pillow-block F, I provide on said block a pillow K, having a concavity i in its upper side, and equip the body with a head L of circular form in cross-section, as 85 shown in Figs. 2 and 3. The head L is designed to rest in the concavity of the pillow and form a rocker bearing or joint which rests in the longitudinal center of the car and in the same horizontal plane as the ball-and-socket bearing between the body and pedestal E. From this it follows that when the body H is inclined or canted in either direction it will bear on the ball G and pillow K and will 90 be held by the latter bearing against swinging or swaying in a horizontal direction.

The body H is normally secured against swinging laterally by a spring-pressed bolt M, which is movable in a suitable guide or guides

j and the aperture *c* of the pedestal, and is designed to take through an aperture *k* in the strap *J*, as shown. To the bolt *M* is connected a hand-rod *N*, which extends through a guide-aperture in the pillow-block *F* to the rear end of the car, so as to permit a person standing at such end of the car to release the strap *J* when it is desired to tilt the body laterally.

When the body is returned to its normal horizontal position subsequent to being tilted laterally in either direction, the spring-pressed bolt *M* will enter the opening *k* in the strap *J* as soon as they coincide or register, and thereby automatically secure the body in such position.

In order that the contents of the body may be discharged from the forward end or either side thereof, said body is provided with an end gate *P* and side gates *Q*. These gates are pivotally connected to or hung from standards *R*, rising from the corners of the body, and are normally held against swinging outwardly by keepers *S S'*. These keepers are in the form of rock-shafts, and they are journaled in suitable bearings in the body and are provided at one end with an angular toe *m*, designed to assume a position at the outside of a gate and prevent the same from swinging outwardly, and at their opposite end with a crank-handle *n*. The keeper *S* of the end gate *P* is disposed longitudinally of the body and has its toe *m* at the forward end and its crank *n* at the rear end thereof to enable an attendant to conveniently release the gate *P* after he has disconnected the rear end of the body from the pillow-block *F*. The keepers *S'* are disposed transversely of the body, the crank of one being arranged at the same side of the body as the toe of the other, as shown.

By reason of the construction described it will be noticed that the body *H* may be tilted longitudinally and dumped by simply disconnecting its rear end from the pillow-block and slightly raising said end and turning the keeper *S* to disengage the toe *m* thereof from the gate *P*. All this may be done by a person standing at the rear end of the car with but a minimum amount of effort, and when the body is tilted it will be held against swinging or swaying horizontally by the fixed strap *J*. The body *H* may also be tilted laterally in either direction by a person standing at the rear end of the car, it being simply necessary for such person to disengage the bolt *M* from the circular guide *J* through the medium of the rod *N* and then pull the desired side of the car downwardly. With this done the person mentioned or a second person has but to turn the proper keeper *S'* to release the side gate of the body, when said body will be discharged of its contents.

When desirable, the transverse rock-shafts *S'* may be omitted, and in lieu of the same a gate-latch may be employed at each side of the body, the said latches being arranged to contact with the stringers when the car is

dumped, and thereby release the gates and enable the body to discharge its contents. These latches are common in the art to which my invention appertains, and I have therefore not deemed it necessary to illustrate the same.

The body is held against swinging or swaying horizontally incident to its lateral inclination by the head *L* bearing on pillow *K*, and when it is returned to its horizontal position it is automatically secured in such position by the bolt *M* engaging the arc-shaped or circular guide *J*.

When tilted longitudinally, the body *H* is stopped by and rests on the ends of the stringers, and when tilted laterally it is stopped by and rests on the inclined edges *a* of the pedestal.

The main frame of the car is preferably made up of the stringers, pedestal, and pillow-block described; but it may be of any other construction suitable to the purposes of my invention. It is also obvious that the said frame may in practice be provided with the various appurtenances common to railway-cars.

Having thus described my invention, what I claim is—

1. In a dumping-car, the combination of a main frame, a body, a ball-and-socket bearing interposed between the center of the body and the frame, a transverse rocker-bearing interposed between the body and frame adjacent to one end and arranged in the same horizontal and longitudinal vertical planes as the ball-and-socket bearing, a circular or arc-shaped guide-bar connected at its ends to the body in a hinged manner, and movable in guides in the frame, and suitable means for detachably securing the body against longitudinal inclination, substantially as specified.

2. In a dumping-car, the combination of a main frame comprising a transversely-disposed pedestal having its upper edge inclined in opposite directions, and a transversely-disposed pillow-block, a ball mounted and secured on the pedestal, a pillow mounted and secured on the pillow-block and having a concavity in its upper side, the body having the central socket receiving the ball, and the longitudinally-disposed head of circular form in cross-section, a detachable connection between the end of the body and the frame, a circular or arc-shaped guide-bar connected at its ends in a hinged manner to the body and movable in guides on the pedestal, and suitable means for detachably securing said bar against casual movement, substantially as specified.

3. In a dumping-car, the combination of a main frame comprising stringers having beveled ends, a transversely-disposed pedestal having its upper edge inclined in opposite directions, and a transversely-disposed pillow-block, a ball mounted and secured on the pedestal, a pillow mounted and secured on

the pillow-block and having a concavity in its upper side, the body having the central socket receiving the ball, and the longitudinally-disposed head of circular form in cross-section, the pendent link pivotally connected to the end of the body, the keeper therefor secured to and adapted to turn in the frame, the circular or arc-shaped guide-bar connected at its ends in a hinged manner to the body and movable in guides on the pedestal, the spring-pressed bolt arranged to engage an

aperture in the guide-bar, and a rod connected to said bolt and extending through a guide in the pillow-block, substantially as specified.

In testimony whereof I have hereunto set my hand in presence of two subscribing witnesses.

MICHAEL J. MCKINNON.
